S. B. FETHEROLF

METHOD OF LAUNDERING TOWELING

Filed March 15, 1923

INVENTOR:

Stephen B. Fetherolf

BY

Albert Allen

ATTORNEYS.

UNITED STATES PATENT OFFICE.

STEPHEN B. FETHEROLF, OF CINCINNATI, OHIO.

METHOD OF LAUNDERING TOWELING.

Application filed March 15, 1923. Serial No. 625,376.

To all whom it may concern:

Be it known that I, STEPHEN B. FETH-
EROLF, a citizen of the United States, and
a resident of Cincinnati, in the county of
5 Hamilton and State of Ohio, have invented
a certain new and useful Method of Lau-
ndering Toweling, of which the following
is a full, clear, and exact description, refer-
ence being had to the accompanying draw-
10 ing, forming part of this specification.

My invention relates to the laundering
of toweling in the shape of long strips,
such as are used in towel service devices.

This toweling runs, say twenty-five yards
15 in length and of usual individual towel
width, and the handling of this in the
mechanical washers of laundries has proven
to be quite a problem. There are a number
20 of ways used at present for bundling up
towel strips in laundries, all of which are
reported to me as unsatisfactory, as they
all include some step of forming the ma-
terial into a bundle, and thus the inner
25 layers are protected against the washing
action by the longer layers.

It is the object of my invention to form
a rope out of a long strip of toweling and
make this rope up into a bundle, of which
30 the strands are separate, except for being
tied together enough to hold them. The
essential thing in my process is to make
up the rope-like body, and the form of
bundle is not essential, as the rope-like
35 structure does not so act as to prevent wash-
ing action and also the various strands in
the bundle do not block off the action of
the cleansing fluid from each other.

It is also my object to provide a process
40 for making a washable bundle of a strip
of toweling which requires the simplest
form of machinery, and in one mechanical
adaptation I require merely a perforated
plate or ring, through which my toweling
45 is drawn onto a simple drum, from which
the rope-like structure can be slipped and
tied into a coil, like a coil of rope, with a
string.

I accomplish my process more specifically
50 by those steps, to be hereinafter more spe-
cifically pointed out and claimed, and by
the use of a structure such as will be de-
tailed in the specification that follows.

In the drawings:

Figure 1 illustrates in perspective, the

operation of forming a bundle, from a strip 55
of toweling.

Figure 2 shows a bundle ready to be in-
serted in a washing machine.

In bringing the strips of toweling to the
laundry they may be in the form of a loose 60
bundle of material, or may be in the form
of rolls, wound upon spindles. In this
last form, the rolls are formed in the dis-
pensing apparatus, wherein as the towel has
been wound from a clean roll, it is wound 65
up again in a soiled roll, and this roll is
brought bodily to the laundry.

In either case it is necessary to tie up
the mass of toweling into a bundle in send-
ing it through the washing process, as a 70
long free strip, say twenty-five yards long,
such as is at present in use generally
throughout this country, would not be
handled by a laundry equipment.

This roll or bundle of toweling as it 75
comes from the user may be dropped into
a basket, or the roll itself may be set on a
pair of trunnions, which have not been
shown, as any form of support would serve.

I have shown a machine consisting of a
roller or drum 1, mounted on standards
2, 2. Preferably the bearings for the spindle
3 of the drum are in the form of two mem-
bers hinged together, as at 4, with the upper
member movable and held down by any 80
form of clip 5. Thus by raising the upper
member of the bearing at both ends, the
drum may be lifted out of the support. An
operating handle 6 is mounted on one end
of the drum spindle, and this entire con-
struction may be made as light as desired,
85 because the work done is slight.

I have shown the confining ring, in the
form of a slider, which can travel along as
the toweling is wound onto the drum, as in 90
the familiar instance of a fishing reel or
kite reel.

Thus I have illustrated a pair of stand-
ards 7, 7, upon which are mounted a pair
of rods 8, 8, over which is set a slider 9,
having holes to engage over both rods. On
the upper side of this slider is a ring 10,
100 through which the toweling strip is caused
to pass.

Referring to the drawings, the operation
of the device shown is as follows. The
towel bundle (or it may be roll) 11, is
dumped or supported near the machine, and

the operator takes the end of the strip, and passes it through the ring, and forms a loop over the drum catching the end of the rope-like structure resulting from drawing 5 the towel through the ring, under the loop so formed. He then revolves the drum by means of the handle, as rapidly as he desires, and the towel is accumulated on the drum in non-lapping strands. He then lifts 10 the one end of the drum from its bearing, and slips the rope-like body off of the drum, and ties it together with pieces of string.

This bundle as indicated at 12, in Figure 15 2, tied at 13, is then ready for the washing machine. It will launder throughout, quickly and very effectively as the water can get at every portion of the piece, because the strands do not protect each other.

For laundering toweling which comes in 20 rolls, or loose masses, my device is simple to use, and the mechanism shown is merely for purposes of illustration, as the ring structure could be added to any one of the many roll unwinding devices now used in 25 the laundry. I have used a mere revolving drum, as the simplest method of making a looped up mass of the rope-like body formed by passing the toweling through the ring, and also as the quickest method of getting 30 the toweling out of roll form, when received from the customer in this manner. The friction in the ring will cause the toweling to pull snugly over the drum and thus the rope-like structure will be practically pressed

into the fabric by winding it up on the 35 drum, and will stay when looped up and tied into the bundle for washing.

Having thus described my invention, what I claim as new and desire to secure by Letters Patent, is:—

1. A process of preparing elongated toweling strips into bundles for washing machines which consists in drawing the toweling through a small aperture, to reduce it to a rope-like size, and preparing said rope-like body into a bundle.

2. A process of preparing elongated toweling strips for laundering which consists essentially in first forming a rope-like body out of the long piece and then 50 forming a bundle of said rope-like body.

3. A process of preparing elongated toweling strips into bundles for washing machines, which consists in drawing the toweling through an orifice, to form a rope-like body thereof, and then winding the said body onto a drum, and finally taking the coils thereof off of said drum, and forming them into a bundle.

4. A process of preparing elongated toweling strips into bundles for washing machines which consists in drawing the strip through an orifice by means of a drum, thereby forming said strip into a rope-like body and practically pressing it 65 into said form, and finally forming a bundle for washing from said rope-like body.

STEPHEN B. FETHEROLE.
